NARROW EMBROIDERED FABRIC
OR THE LIKE

Beatrice Friedman, New York, N. Y.

Application August 22, 1950, Serial No. 11,876

Term of patent 7 years

(Cl. D92—1)

To all whom it may concern:

Be it known that I, Beatrice Friedman, a citizen of the United States, residing in New York city, in the county of New York and State of New York, have invented a new, original, and ornamental Design for a Narrow Embroidered Fabric or the like, of which the following is a specification, reference being had to the accompanying drawing, forming part thereof.

The figure on the drawing is a plan view of a narrow embroidered fabric or the like showing my new design.

I claim:

The ornamental design for a narrow embroidered fabric or the like, substantially as shown.

BEATRICE FRIEDMAN.
